UNITED STATES PATENT OFFICE

JAMES W. SMITH, OF CLEVELAND, OHIO

WINDOW SASH CONSTRUCTION

Application filed February 26, 1929. Serial No. 342,919.

My invention is an improvement in sash balances and relates more particularly to a device for counterbalancing the weight of a sash wherein the ordinary sash balancing weight and hollow jamb may be dispensed with.

One of the objects of my invention is to dispense with the customary sash weight and hollow jamb construction and to counterbalance the sash by means of springs capable of being placed under tension when the sash is moved in its casing.

Another object of my invention is to effectively weatherstrip a sash and casing therefor of the type herein described.

Another object of my invention is to provide a sash balance capable of being placed under tension when the sash is moved in the casing and cooperating with suitable means, whereby air currents and moisture will be prevented from passing between the sash and the casing from one side of the sash to the other.

Another object of my invention is to simplify the sash and casing construction whereby the counterbalancing means may easily be removed from the sash or casing for repair.

Other objects and advantages of my invention will become more apparent as the following description of several embodiments therefor progresses, reference being made to the accompanying drawings in which like reference characters are employed to designate like parts throughout the same.

In the drawings—

Fig. 1 is a front elevation of one side of a sash and casing partly broken away to illustrate one embodiment of my invention.

Fig. 2 is a side elevation of a portion of the sash taken on line 2—2 of Fig. 3 showing the pinion engaging the weatherstrip.

Fig. 3 is a section taken on line 3—3 of Fig. 1.

Fig. 4 is a detail view of the rear shaft bearing assembly and supporting means for the rear end of the shaft.

Fig. 5 is an end view of a modified form of my invention.

Fig. 6 is a sectional view taken on a plane indicated by the line 6—6 of Fig. 5.

Fig. 7 is a sectional view taken on a plane indicated by the line 7—7 of Fig. 5.

Fig. 8 is a detailed view of the rear bearing for the spring shaft.

Fig. 9 is a cross sectional view of the bearing taken on a plane indicated by the line 9—9 of Fig. 8.

Referring now more particularly to Figs. 1 to 4 inclusive, which illustrate the preferred form of my invention, the sash 1 is slidable in a casing 2. The side members 3 of the sash are provided with longitudinal grooves 4 extending throughout the length of the sash. These grooves receive a substantially U-shaped weatherstrip 5 having flanges 6 turned outwardly to engage the casing and to be secured thereto by means of the fasteners 7. It will be noted that the body of the U-shaped weatherstrip 5 extends into the groove in the sash to effectively prevent the passage of air currents and moisture between the sash and the casing from one side of the sash to the other. One side of the U-shaped member adjacent one of the flanges 6 is provided with a series of aligned perforations 8 which are engageable by the teeth 9 of a spur gear 10.

A tubular shaft 11 is rotatably fitted in a bore 12 in the sash as shown in Fig. 1, the forward end of the shaft having fitted into its end a stub shaft 13 which extends forwardly through an opening in the bearing plate 14, and is rotatably supported therein. The gear 10 is secured on the outer end of the shaft 13 and is spaced from the bearing plate by means of a spacing washer 15. It will be noted that the bearing plate 14 and the gear 10 are set into the sash rail 3 behind the outer edge of the sash rail 3. The stub shaft 13 is telescoped within the tubular shaft 11 and they are secured in such position by means of a cotter pin 16. I have provided a duct or groove 17 in the stub shaft which communicates with the interior of the tubular shaft for conveying lubricant to the wick 18 therein. In this manner lubrication of the rear thrust bearing is assured at all times. The rear end of the shaft 11 is rotatably supported in an

end of a sleeve 19 supported by a bolt or screw 20 in alignment with the shaft 11. I have provided a thrust bearing 21 for the shaft 11 which may be a ball bearing having bearing contact with the annular edge of the tubular shaft and with a transverse split or cotter pin 22 passing through the sleeve 19.

By this means I have provided a thrust bearing for the shaft which permits the shaft to be freely and rotatably supported at its rear end in the sash. A coil spring 23 is anchored at its forward end in the looped end of the cotter pin 16 and at its rearward end in the looped end of the pin 22. This spring is supported axially on the shaft 11 and is of sufficient convolutions so that it may be originally tensioned to counterbalance substantially the full weight of the sash.

Thus it will be seen that as the gear 10 is rotated together with the shaft and the spring is placed under tension a thrust will be exerted toward the right in Fig. 1 against the ball bearing 21, the bearing reducing to a minimum the friction which would ordinarily be encountered by a thrust in this direction.

In use this embodiment of my invention operates as follows:

The spring 23 is originally tensioned to counterbalance substantially the full weight of the sash, by rotating the gear 10 by means of a suitable tool, or by raising or lowering the sash in the casing before the same is permanently set therein. When the spring is wound by moving the sash in the casing, the gear may be held against accidental rotation in the opposite direction while the sash is removed and replaced in the casing to further wind up the spring. When sufficient tension has been applied to the spring the sash is replaced in the casing for use, the teeth of the gear 10 operating in the aligned perforations of the weatherstrip 5. As the sash is raised the tension of the spring is decreased, while in lowering the sash the spring tension is increased, the entire range of tension of the spring as originally tensioned being sufficient to counterbalance substantially the weight of the sash during its movement in the casing. The weatherstrip 5 not only provides a rack for the pinion 10, but extends into the groove 4 of the sash sufficiently to effectively prevent the passage of air currents or moisture between the sash and the casing from one side of the sash to the other. It will be noted that the bearing 21 is supplied at all times with a lubricant by means of a wick 18 in the tubular shaft 11.

In Figs. 5 to 9 inclusive I have illustrated another embodiment of my invention which is similar in some respects to those described in Figs. 1 to 4. In this embodiment the shaft 11 is rotatably supported at its rear end in a sleeve 19 and is axially spaced therefrom by the thrust ball bearing 21. A roller

40 is keyed to the stub shaft 13, which extends through the plate 42 and is provided with a tire 41 preferably formed of rubber or other material giving adequate traction with a metallic surface.

The plate 42 is bent at its ends into a substantially U-shape as indicated at 43 for supporting anti-friction rollers 44 on the shafts 45, the rollers 44 being in alignment with the roller 40 and being sufficiently spaced therefrom to engage the body of the substantially U-shaped weatherstripping member 5.

Referring more particularly to Fig. 6, it will be seen that the weatherstrip 5 is engageable on one side by the anti-friction rollers 44 and on its other side by the tire of the traction roller 40. Consequently when the sash is raised in the casing, the traction be-

tween the roller 40 and one side of the member 5 will be sufficient to rotate the shaft 11 against the tension of the spring 23 throughout the limit of movement of the sash in the casing, while the rollers 44 serve to maintain the U-shaped member 5 in intimate contact with the tire on the roller 40. I

have provided means for exerting a pressure on the shaft 13 in a direction toward the substantially U-shaped member 5, which will also increase the traction between the roller 40 and the member 5. This means is

illustrated more clearly in Fig. 5 and consists of a spring 46 anchored at one end 47 in the plate 42, and having its body portion bent about a pin 48. An arm 49 of the spring extends from the pin and its forward end is curved about and engages the shaft 13 between the roller 40 and the plate 42.

In each form of my invention illustrated and described herein it is desirable to provide similar counterbalancing and weatherstripping means on each side of each sash, in which case the springs 23 carried by the shafts 11 in each sash should be oppositely wound. The use of counterbalancing means such as I have disclosed herein on each side of the sash will insure ease of movement of the sash in the casing and will eliminate any tendency of the sash to stick, since substantially equal tensions are applied to the respective springs of each sash in any position of the sash in the casing.

It will also be seen that I have provided a very effective weatherstripping for the sash and casing, which in certain of the embodiments described herein form a part of the counterbalancing means.

Various changes may be made in the details of construction and arrangement of parts without departing from the spirit of my invention or the scope of the subjoined claims.

I claim:

1. The combination with a longitudinally grooved sash and a casing therefor, of a sash balance comprising a substantially U-shaped strip slidable relative to the sash in the sash

groove, a spring within the sash and capable of being placed under tension, means for transmitting tension to and from the spring, said means being engageable with said U-shaped strip outwardly extending longitudinal flanges on said U-shaped strip normal to the U-portion and lying against the surface of the window casing so as to substantially cover the portion thereof exposed to the sides of the sash.

2. The combination with a sash and a casing therefor, said sash having a longitudinal groove along each side spaced from the edges thereof, of a sash balance comprising a spring enclosed in the sash, normally under a tension to substantially counterbalance the full weight of the sash, weatherstrips carried by the casing and extending into the grooves in the sash and means engageable with the weatherstrips to vary the tension of the spring as the sash is moved in the casing whereby an effective weather seal and rack is formed.

3. The combination with a sash and a casing therefor, said sash being provided with longitudinally extending grooves along its sides spaced from the edges thereof, of a sash balance comprising a spring enclosed in the sash, normally under a tension to substantially counterbalance the full weight of the sash, a weatherstrip carried by the casing and covering that part of the surface of the casing adjacent to the sides of the sash, a portion of said weatherstrip being bent outwardly from the frame to form ribs extending into the grooves in the sash, and means engageable with the weatherstrip to vary the tension of the spring as the sash is moved in the casing, said means including a shaft axially aligned with the spring and a gear on an end of the shaft, said weatherstrip having a series of perforations engageable by the teeth of the gear whereby the seal between the sash and casing is entirely enclosed and the frame and seal are protected.

4. The combination with a sash and a casing therefor, said sash having longitudinal grooves along its sides spaced from the edges thereof, of a sash balance comprising a spring enclosed in the sash, normally under a tension to substantially counterbalance the full weight of the sash, a weatherstrip carried by the casing and extending into the grooves in the sash, and means engageable with the weatherstrip to vary the tension of the spring as the sash is moved in the casing, said means including a shaft axially aligned with the spring and a roller on one end of the shaft, said roller being in intimate contact with one side of said strip whereby the tension of the spring may be varied when the sash is moved in the casing.

5. The combination with a sash and a casing therefor, said sash being grooved along its sides, of a sash balance comprising a spring

enclosed in the sash, normally under a tension to substantially counterbalance the full weight of the sash, a weatherstrip carried by the casing and extending into the groove in the sash, means engageable with the weatherstrip to vary the tension of the spring as the sash is moved in the casing, said means including a shaft axially aligned with the spring and a roller on one end of the shaft, said roller being in intimate contact with one side of said strip whereby the tension of the spring may be varied when the sash is moved in the casing, and means engageable with the other side of the strip to increase the traction between the roller and the strip.

6. The combination with a sash and a casing therefor, said sash having longitudinal grooves along its sides spaced from the edges thereof, of a sash balance comprising a spring enclosed in the sash, normally under a tension to substantially counterbalance the full weight of the sash, a weatherstrip carried by the casing and extending into the grooves in the sash, and means engageable with the weatherstrip to vary the tension of the spring as the sash is moved in the casing, said means including a roller, said roller being in intimate contact with one side of said strip whereby the tension of the spring may be varied when the sash is moved in the casing, and means for increasing the traction between the roller and strip.

In testimony whereof, I hereunto affix my signature.
